OTHER PUBLICATIONS

Light Fixture shown in May 2010.

Primary Examiner — Clare E Heflin

(74) *Attorney, Agent, or Firm* — Jansson Munger McKinley & Shape Ltd.

(57) **CLAIM**

The ornamental design for a lighting fixture, as shown and described.

DESCRIPTION

FIG. 1 is a perspective view of the lighting fixture;
FIG. 2 is a right-side elevation of the lighting fixture of FIG. 1;

FIG. 3 is a left-side elevation of the lighting fixture of FIG. 1;
FIG. 4 is a bottom plan view of the lighting fixture of FIG. 1;
FIG. 5 is a top plan view of the lighting fixture of FIG. 1;
FIG. 6 is a front elevation of the lighting fixture of FIG. 1;
FIG. 7 is a rear elevation of the lighting fixture of FIG. 1;
FIG. 8 is a perspective view of a second embodiment of the lighting-fixture design, the primary difference being a pole fitter shown in phantom lines;
FIG. 9 is a right-side elevation of the lighting fixture of FIG. 8;

FIG. 10 is a left-side elevation of the lighting fixture of FIG. 8;
FIG. 11 is a bottom plan view of the lighting fixture of FIG. 8;
FIG. 12 is another bottom plan view of the lighting fixture of FIG. 8 showing the light fixture without the pole fitter;

FIG. 13 is a top plan view of the lighting fixture of FIG. 8;
FIG. 14 is a front elevation of the lighting fixture of FIG. 8;
FIG. 15 is a rear elevation of the lighting fixture of FIG. 8; and,
FIG. 16 is another rear elevation of the lighting fixture of FIG. 8 showing the light fixture without the pole fitter.
The phantom lines are provided for illustrative purposes only and form no part of the claimed design.

1 Claim, 14 Drawing Sheets
